FRANKLIN H. WOLEVER, OF CHICAGO, ILLINOIS.

SAND-BLASTING MACHINERY.

Application filed February 4, 1924. Serial No. 690,387.

This invention relates to improvements in sand blasting apparatus of that type that employs air at a high pressure as a medium of propelling sand or other abrasives at 5 high velocity through a nozzle against metallic or any other substance to be treated.

Among the common faults with sand blast apparatus now in commercial use may be summed up the following; lack of positive 10 sand flow, which causes intermittent volume variations of sand flow and varying velocities; lack of means for separating from the clean sand detritus, dust, and the like, whereby same properly cleaned sand can be used 15 over and over; inconveniently located manual controls remote from operative points, lack of proper provisions for ready access to vital parts of the operative mechanism to remove obstructions; lack of means for 20 establishing sand flow after the sand blast has been shut off without experimentation with the sand and air valves, and inconvenient means for filling the sand tank after it has been emptied. In the operation of 25 many types of machines, the operatives are required to wear dust masks in order to protect themselves against clouds of dust that arise from the sand blasting operation.

The purpose of the present invention is to 30 overcome the above objections and to provide a sand blast apparatus having many other desirable features that will be more fully set out in the following description.

The foregoing brief statement of the construction and operation is made for the purpose of a survey before proceeding with a detailed description of the present embodiment of the invention and for the purpose of indicating the nomenclature herein 35 observed to anticipate the general steps of the operation of the apparatus. It is to be understood that said statement is merely descriptive and is not intended to be limiting.

In the drawings:

40 Figure 1 is a side elevation of the machine and an end view of the car or work support.

Figure 2 is a front view of the machine with the car or work support in place.

Figure 3 is a horizontal section on line 45 3—3 of Figure 2.

Figure 4 is a vertical section on line 4—4 of Figure 3.

Figure 5 is an axial section through the sand tank and car.

Figure 6 is a cross section through the single stage sand jet on line 6—6 of Figure 5.

Figure 7 is a cross section through the sand jet receiving chamber at the bottom of the sand tank taken on line 7—7 of Figure 6.

Figure 8 is a cross section through the jet pump delivery on line 8—8 of Figure 4.

Figure 9 is a cross section through the jet pump to nozzle on lines 9—9, Figure 4.

As shown in the drawings, A is the operator's platform; B the shuttle car containing the blasting chambers B¹; C the intake chamber of the sand cleaning and dust separator connected through an S-shaped trap E and conduit G at the converging outlet of 50 said chamber to a cyclone or dust collector D and exhausting through an exhaust fan D¹ to the atmosphere. G' is a sand pit below the separating chamber into which the sand falls through the grid-like bottom of 55 said chamber. H is a sand tank to which clean sand is lifted from the sand pit below through the action of a jet pump I (Figures 1 and 2) which receive air under pressure 60 through a pipe I¹ from any suitable source 65 and discharges the sand through a pipe I² to a receiving chamber H¹ above the clean sand chamber H when the sand is discharged into 70 a sand chamber H. The sand is fed in the 75 operation of the machine through the hopper 80 bottom of the tank and through a sand measuring apparatus J (Figures 1 and 5) 85 and thence through the nozzle hose K to the 90 manually operated jet nozzle K¹ by which 95 the blasting sand is directed at suitable 90 velocity and volume onto the work in the sand blasting compartments B¹.

The car B is divided into the blasting compartments by partitions 15. Said compartments are equal in width to the front 95 end of the receiving end of the chamber C. The tracks 19 on which the car rests and rolls are provided with bumpers 20 to properly line the compartments relatively to the front open end of the chamber C. The work to 100 be treated is supported on turntables 16 within the compartments, said turntables being mounted on the upper ends of vertical shafts 17. The turntables can be manually turned to present the work to the sand blast 105 from the nozzle K¹ when the latter are in the position shown in Figure 5. The work is preferably directly supported on remov-

able wear plate 18 which can be replaced at small cost when worn by the sand blast.

The bottom 21 of the chamber C is of grating or grid-like structure to permit the clean sand to fall freely to the sand pit G' below. The roof 22 of the chamber C is solid from front to rear. At its front it has an upwardly flaring wall 23 terminating in a forwardly extending wall 24 which 10 constitutes a hood to extend over the blasting compartments B¹ and to furnish a large free air intake to the chamber C. Said hood is closed at its ends by end walls 26 to afford proper direction for the incoming 15 air. Rubber or other flexible strips 28, fastened preferably to a suitable vertical part of the chamber C cooperate with the partitions 15 of the chamber C to close the openings between the blasting compartments 20 and the separator chamber C.

The vertical side walls of the chamber C comprise outer solid plates 30, which converge towards the rear end of the chamber, and inner louver plates 31 which are disposed at angles to the walls 30 and in planes parallel to each other. They relatively overlap each other with their forward edges spaced furthest from the plates 30 to form the vertical louver slits 32. The sand passes 30 through said slits into the spaces between said louver strips and the solid plates 30 and falls into the pit below through slits 33 in the chamber floor (Figure 3).

The S-shaped trap E at the narrower discharge end of the chamber is located over the rear end of the sand pit G'. It is considerably restricted in width but is about the same vertical depth as the chamber side walls. The side walls of said trap outlet 35 are composed of solid and louver plates 34, 35, respectively, and intervening bottom wall slits 36 therebetween permit the sand caught between the louver and solid plates to flow into the sand pit. The outlet leg 40 of the indirect discharge passage thus formed communicates throughout its height with a dust and air discharge opening 37 (Figures 2 and 5) which communicates through the conduit F and its flaring outlet 45 into the cyclone or dust separator D of any suitable construction. If desired, the floors of the trap may be provided with gravity operated trap doors 40, normally held closed by springs 42 acting between arms 43 on 50 said hinged trap doors and rigid arms 44 on the adjacent structure (Figure 5). The presence of said doors, when operating with relatively light sand, to avoid drawing the sand out of the rear part of the sand pit at 55 the point where the velocity of the air is high. The springs 42 can be so adjusted that the doors will be operated with a moderate weight of sand to dump sand into the pit beneath, while normally serving to prevent current of air being established below

the level of the chamber floor at the rear thereof which would have a tendency to carry sand upwardly from the pit into the separator G. Moreover, these trap doors permit all the sand to be discharged from 70 the separating chamber and its outlet when it is desired to entirely clean the sand from the machine, the doors being adapted to be manually opened for such purpose.

The broken lines in Figures 3 and 5 indicate the manner in which the sand is deflected from the work W on the turntables 16, and the arrows in Figure 5 indicate the manner in which the air is drawn into and through the chamber and thence to the dust 75 collector D at high velocity to take up the dust and the lighter portions of the sand and the particles broken or blasted off the work. While the air carries the lighter material to the dust collector, the heavier 80 clean sand falls by gravity to the sand tank G through the openings in the grid-like bottom and the openings 33 and 36 behind the louver plates. It will be noted from an inspection of Figure 5 that the sand and 85 detritus due to the blasting operation is discharged into the chamber C at an upward angle, due to the angle at which the jet meets the work. The blast also leaves the work in a flaring or fan-like shape, as shown 90 in Figure 3. The form of the separating chamber is such that the sand and particles removed from the work by the blasting operation enters the front of the chamber C in a 95 rather loose spraylike form or with the particles interspaced, so that the separating air drawn into the chamber through the exhaust fan D' can pass freely through and among the particles to separate and carry the lighter dust and detritus from the relatively 100 heavier particles of sand or other blasting material. The air enters the front of the chamber throughout its height, as indicated by the arrows in Figure 5, and by reason of the area of the orifice thereat, the air passes 105 into the chamber at relatively slow velocity and large volume; and its speed increases as it passes to the rear restricted portion thereof. By reason of the angle at which the sand enters the chamber the inwardly 110 flowing air has large and intimate contact with the inwardly projected mass of said detritus and blasting clips and has an opportunity to separate the lighter from the heavier particles thereof. This intermingling of the sand and air is also promoted by reason of the fact that some of the sand 115 strikes the louver plates at angles which again throws the sand back towards the center of the chamber for action thereon by 120 the cleaning air. As the air approaches the rear restricted end of the chamber its velocity increases so as to sustain the dust and light particles therein on the way to the dust separator D through the trap E. 130

A greater portion of the sand will have been separated by gravity from the rearwardly moving mass before the mass reaches the trap, but such particles of usable sand as 5 are carried therebeyond will be separated by the louver plates 35, due to the centrifugal force of the sand particles as the mass is passing through the bends of the traps. Any dust that may not be removed from the 10 sand as it is deposited into the pit will be removed while the sand is being transferred from the pit, through the receiver H' to the sand tank H, as hereinafter described.

In the operation of the type of the machine 15 shown, the sand tank H is first filled with sand. When beginning the operation, the sand will be drawn from a source of sand supply outside the machine. After the machine is in operation, the supply of sand 20 will be that in the sand pit G', and it is withdrawn therefrom through the action of the sand pump I (Figures 1, 5, 6 and 7). The said pump operates in a depression or trough 45 located at the bottom of the pit 25 to receive all the sand from the pit by the natural flow line of the sand. The pump embraces a cylinder 46 (Figures 6 and 7) that communicates through a top opening 47 with the sand pit. To one end of said cylinder 30 is connected the valve air pressure pipe I' adapted to be connected with any suitable source of air under pressure. Said air pipe I' discharges into a chamber 50, one wall 51 of which, within the casing 46, receives a 35 jet nozzle 52 that lies in the axis of the said casing 46. The said wall 51 is provided below its axis with a plurality of openings 53 (Figure 6). The pipe I' leads from the cylinder 46 in axial alignment with air jet 40 nozzle 52. Therefore, when air under pressure is delivered to the chamber 50, its jets through the pipe 52 and the openings 53 and acts with an injector effect to force the sand through the pipe I' and raise and deliver it to the receiver H' of the sand 45 tank H.

Said pipe I' leads tangentially into the side of the receiver, as shown in Figures 4 and 8. The speed of the sand thereby is 50 reduced and the sand is agitated as it enters the said receiver by impact against a series of radial projections 55 in the receiver of unequal effective heights, so that the sand is free to drop by gravity to the bottom of the 55 receiver. The lighter particles are carried by air away from said receiver back to the rear part of the chamber C to be carried to the collector D by means hereinafter described.

60 The bottom of the receiver communicates with the tank H through an opening controlled by a cone-shaped valve 56, which controls the flow of sand from the receiver to the tank. Said valve is vertically movable 65 and seats upwardly against a ring 57, which,

as herein shown, is within the top of the tank H in axial alignment with the receiver and constitutes a continuation thereof. The ring is fixed in any suitable manner to the top wall h of said tank, and its lower seating face is formed by an annular tapered body of resilient substance 58, such as rubber, to produce an air tight joint between the cone-shaped valve and said seat, for a purpose presently to appear. The said 70 valve has a vertical stem which extends upwardly through a tubular guide 60 carried by a spider within the receiver, and through a neck 61 having at its upper end a stem guide 62. An expansion spring 63 is interposed between an upper face on said neck and a shoulder 64 on the stem above the neck (formed by a threaded nut) and acts normally to hold the cone-like valve against its tapered seat. 75

A pipe 68 communicates with the upper end of said neck and discharges into the chamber C through its top wall 22 and serves to withdraw dust and light particles from the agitated sand in said receiver. Thus 80 the sand is subjected to a further cleaning action before it is discharged into the sand tank. When the sand tank is to be filled, the jet pump is set in operation to raise the sand from the sand pit into the receiver H', 85 and the agitation of the sand as it enters the receiver, due to its impact against the wings 55, serves to reduce the speed of the sand and to cause the sand to drop by gravity and the dust and lighter particles to be separated 90 from the sand by the action of the draft of air through the pipe 66, due to the low pressure in the chamber C, so that the sand is prepared in readiness for entrance into the tank in a clean condition. 100

The seating strength of the spring 63 can be so regulated, as by the nut 64, that a given weight of sand overcomes it and opens the cone-like valve to allow the sand to flow by gravity into the tank below. The said 110 spring 63, regulated as it is, cooperates with gravity to control the sand flow until the tank has been filled, and after the operation of the sand jet pump has been stopped, the said spring acts to hold the valve hard 115 against its seat to provide a joint against the escape of air through the filling valve thus described during the sand blast operation.

An air vent is established from the tank 120 while the tank is being filled through a vent pipe 68, the top of which opens near the top wall of the tank (Figure 4). Said vent pipe extends downwardly through the hopper bottom of the tank and is provided 125 exterior to the tank with a branch 69 which discharges into the air. As herein shown, and for a purpose hereinafter to be described, the said branch opens into a chamber 70, which can be fastened to the tank 130

structure. Said chamber is provided at its bottom with an outlet or vent opening 71 which is adapted to be open when the sand tank is being filled, so as to equalize the tank pressure with the atmosphere; but said opening is adapted to be closed during the blasting operation to equalize the tank pressure with the operating pressure. To this end, the vent or equalizing pipe extends beyond the outlet branch 69 to form an extension 70', for a purpose presently to appear.

After the sand tank is filled, the sand is discharged in measured quantities therefrom through the nozzle K' under the control of a suitable volume and pressure control means. One embodiment of said control means is best shown in Figure 4, and is made as follows:

75 designates a rotative measuring bowl which is axially below the discharge nozzle 76 of the sand tank at the conical lower end of the tank. As shown, the nozzle is formed as an integral part of the casing 77 of a measuring device and the smaller discharge 25 of the said tank is flanged for attachment to the upper flattened end of said casing, with the tank discharge 76 in line with said nozzle. The measuring bowl is fixed to and rotates with a vertical stub shaft 78 which 30 is rotatively mounted in a bearing 79 that is carried by and is partly enclosed in a shell 80 of suitable form to protect said bearing from dust and sand. The bearing is further protected at the point where the 35 hub of the bowl and the bearing members meet by a skirt 80' which is arranged in overlapping relation to the upper conical end of said shell 80. Fixed to the lower end of said shaft 78 is a beveled gear wheel 81 that meshes with a beveled pinion 82. Said pinion is fast to the inner end of a shaft 83 that is mounted to rotate in a bearing 84 which is carried by the casing 77. The lower, tapered end 85 of the measuring device casing has the form of a neck 86 that can be made integral with a fitting 87, herein shown to be the casing of a sand pump, through the medium of which sand is delivered from the measuring device casing to the sand discharge tube and nozzle, as will hereinafter be described.

The shaft 83 is fixed to a worm gear 88 which meshes with a worm 89 that is fixed to and rotates with the shaft of an air turbine 90 (Figure 4). Said worm gears are enclosed in a suitably shaped sand proof casing to protect them from sand and dust. 91 designates the casing of the air turbine 90, one side of which casing is open to one 95 branch 106 of a pressure pipe 92. Said pipe 92 has a flanged, axial connection at its lower end with the tapered receiving end 93 of the sand pump casing 87, there being a pressure chamber 94 formed in said tapered 100 formation 93 between the adjacent end of

the pipe 92 and a transverse wall or partition 95 in said sand pump casing 87.

Connected to the end of the pipe 92 remote from the sand pump is a pipe 97 for delivering air under pressure to the pipe 92, 70 for the double purpose of furnishing air to operate the turbine and for operating the sand pump by which the sand is forced through the nozzle K'. Said pipe 97 has a cut off and controlling valve 98. The pipe 75 97 communicates with the pipe 92 through one lateral branch of a fitting 99, another branch of the fitting being connected directly to the conduit 92. Said fitting is valve controlled to shut off air pressure from 80 the pipe 97 when the sand tank is being filled and when the blasting operation is discontinued. A valve 100 for this purpose is shown in Figure 4 as being closed.

Said valve 100 is a tapered faced closure 85 to engage a like-shaped seat in a diaphragm of the fitting 99. The stem 101 of said valve extends through a stuffing box at the top of the fitting, and is connected by a coupling 102 with the lower end of a stem 103. The stem 103 extends upwardly through a chamber 104 made of upper and lower casing members and is connected to a diaphragm 105 which extends across said chamber, with the margin thereof confined 95 between the margins of the members of the two part casing in a known manner. Said stem 103 extends through a stuffing box in the lower casing member to maintain air tight the lower chamber 104 of said casing. 100 The stem is surrounded in its part between said diaphragm and the top member of the casing by a spiral expansion spring 107, the normal tendency of which is to close said valve 100. The upper end of the stem 103, above the casing 104, carries a disc 105 valve 103' to close the vent opening 71 in the equalizing chamber 70 before referred to.

Located within the conduit 92, abreast the air turbine, is a partition 105' which is free at its upper and lower ends from the conduit wall and, in effect, provides two branch conduits 106, 107, the former of which directs air to the vanes of the turbine, and the latter of which shunts air from the turbine blades and directs it to the sand pump beneath the measuring mechanism. The said branches 106, 107 are adapted to be separately controlled to vary the volume of air passing therethrough by any suitable control or throttle means such, for instance, as by means of studs 108, 109 that are threaded through the opposite walls of the conduit and are adapted at their inner ends to approach and recede from the partition 115 105.

The sand pump at the discharge end of the volume measuring mechanism is generally similar to the sand pump which raises the sand from the pit to the receiving cham- 130

ber of the sand tank. It embraces, in addition to the parts already described, a tube 110 (Figure 4) which lies axially within the casing 87 and is fixed at its rear end in a central opening in the partition 95. Said tube, therefore, affords free passage for air centrally through the pump chamber. The sand falls around the tube 110, as shown in Figures 4 and 9, in front of the partition 95. Said partition 95 has in its lower part a plurality of openings 112. Air, under pressure, therefore, passes through said tube and through said openings 112 and acts with an aspirator effect to forcibly discharge the sand from the pump casing through the nozzle. The nozzle has a restricted throat near its outer end afforded by a liner 114 made of a substance to resist wear. The said liner is flared at both ends and restricted between its ends so as to thereby impose a resistance to sand discharge and to increase the velocity of the sand projected from the nozzle.

Located at, and preferably carried by the nozzle piece is a cut off and control valve, designated as a whole by 115. As shown, its casing is provided with a collar 116 which is clamped about the hose K at the point where it laps over the nozzle piece K¹ to thereby fasten the valve in place and to clamp the hose on the nozzle piece. The casing of said control valve is formed with three tubular branches 117, 118, and 119. The branch 117 opens to the atmosphere. The branch 118 is connected by a flexible hose 120 and a pipe 121 with the lower chamber 104' of the diaphragm casing 104. The branch 119 is connected by a flexible hose 122 and a pipe 123 with the main pressure pipe 97 just inside its valve 98. 124 is a plug that is rotatively seated in said casing and is provided with an actuating handle 125. Said plug is provided with two curved internal ports 126, 127, the ends of which are spaced angular distances apart equal to the angular spacings of the ports in the branches of the casing, the spacings being 90° as herein shown.

In the adjustment of the parts shown in Figure 4 the lower chamber 104' of the diaphragm chamber 104 is open, through the port 127 in the plug, to atmosphere, so that the spring 107 is at this time active to close the valve 100 and to open the sand tank vent 71. If the plug be turned 90° to the left from the position shown in Figure 4, the port 126 will connect the pressure pipe 97 with said lower chamber 104' of the diaphragm casing 104, whereby the pressure of said pipe 97 is effective to raise the diaphragm 105 to open the valve 100 to admit air under pressure to the conduit 92, and thereby to the air turbine and the sand pump. Such air line pressure is also operative to close the valve disc 103' against the sand tank vent opening 71. These are the

operative positions of the parts for sand blasting. 128 designates a branch which leads from the extension of the equalizing pipe 68 and communicates with the casing 77 enclosing the sand volume control mechanism, where pressure in said casing and the tank can be equalized during the sand blasting operation of the machine.

It is desirable that means be provided for limiting the effect of the sand head in the tank H, so as to thereby reduce the feed velocity of the sand from said tank to the measuring device. This result can be effected by arranging a cone-like shelf or diaphragm 130 within the sand tank above its discharge nozzle 76, and supporting it centrally in said tank by brackets 131 from the wall of the tank. This central support or shelf will modify the flow line of the sand in the manner indicated in said Figure 4, and reduce the head pressure of the sand at the outlet nozzle to an extent represented by the area of said shelf.

In order that free access may be had to the outlet of the tank to remove clogging obstructions, a hood 132 is arranged below said shelf transversely across the conical lower end of the tank. The hood can be supported on opposite walls of the tapered portion of the tank. At one end of said hood the tank wall is provided with a hand hole 133, covered by a suitable closure. Through the hand hole any suitable implement can be inserted into the restricted outflow of the tank to clear the outflow of any obstruction that may lodge there. The presence of said hood, to the extent that its side margins intercept the normal flow line from the margins of said shelf 130 further reduces the sand head pressure at the tank outlet.

The various parts of the apparatus may be supported in any suitable frame, such as is shown in the drawings, but, inasmuch as the particular character of the frame work will depend somewhat upon the installation, it has not been deemed essential to describe such work in detail.

The operation of the apparatus may be briefly stated as follows:

The work to be sand blasted is placed upon the turntables of one of the blasting compartments and the car or support is shifted to bring said compartment opposite to the chamber C. The motor 135 which drives the exhaust fan D' is started, and the fan creates a high velocity and large volume of air flow through the front of the chamber C and rearwardly thereof and thence through trap E and conduit F to dust separator D, whence the air is driven to atmosphere. This current of air is calculated to draw a volume of air through front of machine to equal at least four times that blown through the sand blast nozzle, and this increased volume dis-

placement will carry all fine dust blasting detritus and the fine particles of sand that are no longer useful through the sand separator and into the dust collector D. The sand thus cleaned falls through the grid-like floor of said chamber and is deflected by the louver-like formation of the side walls of the chamber and trap to the sand pit below, from whence it is raised by the said pump 10 and is further cleaned in the receiver and deposited into the sand tank H.

To start sand blasting, the compressed air valve 98 is turned on, and the operator takes the nozzle K' piece in his hand and turns the control valve plug to a suitable stop (not shown) which registers the port 126 with the proper casing ports to connect the pressure pipe 97 to the chamber 104' beneath the diaphragm. The increased area 20 of surface of the diaphragm over the net surface of the valve 100 causes the valve 100 to lift and to thereby compress spring 107 and to also cause the disc valve 103' to seat against and close the vent port 71 through 25 which the tank pressure was theretofore equalized with atmosphere. The sand tank is now sealed off from the atmosphere and compressed air now flows through valve 97 through the opening controlled by the valve 30 100, and thence through the branch passages 106 and 107 of the conduit 92. A portion of the air is passed through the passage 106 over the vanes of the turbine to drive the same and another portion is diverted through 35 the branch passage 107 to the chamber 94 at the rear of the nozzle sand pump, and thence through nozzle hose K and the nozzle K'. The air pressure built up in the chamber 94 of the sand pump carries the sand delivered 40 to the pump casing through the hose and discharges it from nozzle K' onto the work W.

The small area of the nozzle K' as compared to the area of intake air passages 110, 112, builds up pressure in chambers 94 and 45 77, which is soon equalized in the tank by flow of air from said chamber 77 through the equalizing branch 128 and pipe 68 to the tank (Figure 4). This pressure also serves to seat the sand feed control cone valve 56 more tightly than by the action of the spring 63 alone. As soon as pressure is equalized in 50 the tank, the casing 77 and the said pump, sand will begin to flow into cup 75, which is being driven by the turbine 90 at a speed due to the control of the branch 106 which delivers air to said turbine. Rotation of the bowl 75 acts to centrifugally throw the sand delivered thereto outwardly and cause it to flow to the restricted outlet or passage of the 55 casing 77, from whence it is forced to the discharge or blasting nozzle K'. Obviously the more rapidly the bowl is rotated the greater will be the volume of sand delivered down through the nozzle 76 of the sand tank. 60 The control of the speed of this bowl,

through controlling its driving turbine 90 by the action of the valve 108 or equivalent throttling means, has the effect to vary the volume of sand delivered to the sand pump below in a given time. Likewise, the operation of the valve 109 or an equivalent control for the high pressure branch 107 serves to control the velocity at which air is delivered to the chamber 94 of the sand pump. With these controls it will be obvious that 75 the sand volume and velocity discharge at the nozzle can be accurately varied to suit different kinds of work. With a constant feed pressure in the pipe 97, it will be obvious that the valves 108 and 109 will permit a 80 considerable range of relative volume and velocity of air delivered to the turbine and to the pump through the branches 106, 107, with a corresponding variation, as stated, with respect to the volume and velocity of the sand discharged from the nozzle K' onto the work.

When sand from the tank H has been exhausted, the valve 115 at the nozzle K' is turned by its handle 125, so as to close communication from the feed or pressure pipe 97 to the conduit 92 and to the pressure chamber 104' of the diaphragm casing and to establish communication from said diaphragm chamber 104' to the atmosphere. The spring 107 then becomes active on the diaphragm to close the valve 100 and to open the equalizing port 71 so as to equalize the pressure in the tank with the atmosphere. Thereafter the sand pump I is set in operation to again charge the sand tank H, after which the hand valve 115 is adjusted to open the valve 100 to connect the feed pressure pipe to the conduit 92, whereupon the machine is again in position for sand blasting operation.

I claim as my invention:

1. In a sand blasting apparatus, an open front separating chamber, with means to induce a rearward flow of air therethrough to and through a rear outlet, a support for the work in front of said chamber, confining means for directing sand and chips deflected from the work into said chamber and for directing air in large volume through the sand so deflected into said chamber, and a sand pit below said chamber, the side walls of said chamber converging toward the chamber outlet and formed with louver-like slits, backed by solid portions, and the bottom of said chamber being of grate formation to direct sand falling thereon to the said sand pit.

2. In a sand blasting apparatus, a separating chamber open at its front to receive blasting sand and chips deflected from the work being blasted, and having a large air receiving mouth opening over said support, the side walls of said chamber converging towards the rear of the chamber and formed with vertically disposed louver-like slits.

backed by solid wall portions, the floor of said chamber being of grid formation and provided back of the louver-like slits with sand discharge slits, and means connected to 5 the rear end of said chamber to induce a flow of air through its open front and rearwardly through the chamber.

3. In a sand blasting apparatus, a separating chamber open at its front to receive 10 blasting sand and chips deflected from the work being blasted, the side walls of said chamber converging towards the rear of the chamber and formed with vertically disposed louver-like slits backed by solid wall 15 portions, the floor of said chamber being of grid construction and provided back of the louver-like slits with sand discharge slits, and means at the rear end of said chamber to induce a flow of air through its open 20 front and rearwardly through the chamber, the rear end of said chamber having the form of an indirect trap, the walls of which are also formed with vertical louver-like slits and imperforate wall portion backing 25 the same and with sand discharge slits in the floor of the trap walls back of said louver-like slits.

4. In a sand blasting apparatus, a separating chamber open at its front to receive 30 blasting sand and chips deflected from the work, the sides of said chamber converging towards the rear of the chamber, the floor of said chamber being partly of grid formation, means connected to the rear end of the 35 chamber to induce a flow of air through its open front and rearwardly through the chamber, a sand pit below said chamber and a trap door in said floor near the chamber outlet opening into said sand pit.

40 5. In a sand blasting apparatus, an open front separating chamber, the side walls of which are slotted and converge toward a rear outlet, and the bottom wall of which is of grid formation, a suction fan connected 45 to said outlet to induce a flow therethrough, a work support in front of said open end of the chamber, and confining and guiding means for directing sand deflected from the work and air into said chamber in a manner 50 to draw the air through the sand to carry rearwardly the lighter particles of the sand stream while allowing the heavier particles to fall to the bottom of the chamber.

6. In a sand blasting apparatus, an open 55 front separating chamber, means to induce rearward air flow therethrough, and a movable work support having two blasting compartments adapted by movement of said support to register one compartment with the 60 front opening of said chamber and to locate the other compartment in work unloading and loading position, said compartments being bounded at the sides by upright walls of substantial height, said walls being so 65 spaced that those at the sides of each com-

partment register with the sides of said chamber when such compartment is in registration with the chamber.

7. In a sand blasting apparatus, an open front separating chamber, means to induce 70 a rearward flow of air therethrough, a wheeled work support provided with two front and rear opening blasting compartments, a track on which said support rests and rolls, whereby either of said compartments may be brought into register with the front opening of said chamber, with the other compartment in unloading and loading position, and stops at the ends of the track to arrest said support with either of 75 its compartments in register with said front opening of the separating chamber, said compartments being bounded at the sides by upright walls of substantial height, said walls being so spaced that those at the sides 80 of each compartment register with the sides of said chamber when such compartment is in registration with the chamber.

8. In a sand blasting apparatus, an open front separating chamber, means to induce 85 rearward air flow therethrough, a movable work support having two blasting compartments adapted by movement of said support to register one compartment with the open front of said chamber and to locate the 90 other compartment in work unloading and loading position, and means associated with the compartment structure and the chamber structure at the sides of the open front thereof to guide deflected blasting material 95 and chips from said compartments to said chamber and to provide dust proof joints between said structures, said compartments being bounded at the sides by upright walls 100 of substantial height, said walls being so spaced that those at the sides of each compartment register with the sides of said chamber when such compartment is in registration with the chamber.

9. In a sand blasting apparatus, an open 105 front separating chamber, means to induce rearward air flow therethrough, a movable work support having two blasting compartments adapted by movement of said support to register one compartment with the open front of said chamber and to locate the other compartment in work unloading and loading position, said compartments being bounded by upright walls and packing 110 means on the chamber structure at the sides of the front opening thereof adapted to engage said compartment walls.

10. A sand blasting apparatus comprising 115 means to jet a flow of sand against the work and deflect it therefrom, means to clean the sand deflected from the work, a sand pit to receive the clean sand, a closed sand tank to the discharge end of which the sand jetting means is connected, a receiver at the top of said sand tank, means to transfer the clean 120

sand from said pit to said receiver, deflecting blades in said receiver against which said tank, the sand transferred from the sand pit to the receiver impinges by impact, a suction pipe connected to the upper part of said receiver, and means at the lower part of the receiver to transfer clean sand therefrom to the sand transferred from the sand pit to the receiver. In witness whereof I claim the foregoing my invention, I hereunto append my signature this 14th day of January, 1924.

FRANKLIN H. WOLEVER.
